UNITED STATES PATENT OFFICE

ARTHUR STOCKSTROM AND ALMER H. BRODBECK, OF ST. LOUIS, MISSOURI, ASSIGNORS
TO AMERICAN STOVE COMPANY, OF ST. LOUIS, MISSOURI, A CORPORATION OF NEW
JERSEY

DESIGN FOR A RANGE

Application filed August 22, 1929. Serial No. 32,514. Term of patent 14 years.

To all whom it may concern:

Be it known that we, ARTHUR STOCKSTROM and ALMER H. BRODBECK, citizens of the United States, residing in the city of St. Louis and State of Missouri, have invented a new, original, and ornamental Design for Ranges, of which the following is a specification, reference being had therein to the accompanying drawing.

The accompanying drawing is a perspective view of a range showing our new design.

We claim:

The ornamental design for a range, as shown.

In testimony whereof, we hereunto affix our signatures:

ARTHUR STOCKSTROM.
ALMER H. BRODBECK.
